(57) **CLAIM**

The ornamental design for a bracelet for containment of and rapid access to personal medication, as shown and described.

DESCRIPTION

FIG. 1 is a right side perspective view of a bracelet for containment of and rapid access to personal medication showing my new design;

FIG. 2 is a front elevation view of the bracelet for containment of and rapid access to personal medication of FIG. 1;

FIG. 3 is a back elevation view of the bracelet for containment of and rapid access to personal medication of FIG. 1;

FIG. 4 is a top plan view of the bracelet for containment of and rapid access to personal medication of FIG. 1;

FIG. 5 is a bottom plan view of the bracelet for containment of and rapid access to personal medication of FIG. 1;

FIG. 6 is a left side elevation view of the bracelet for containment of and rapid access to personal medication of FIG. 1;

FIG. 7 is a right side elevation view of the bracelet for containment of and rapid access to personal medication of FIG. 1; and,

FIG. 8 is a right side perspective view of the bracelet for containment of and rapid access to personal medication of FIG. 1 shown with the medication compartment open to allow access to the medication stored therein.

The broken lines shown in FIG. 8 represent environmental matter which forms no part of the claimed design.
